UNITED STATES PATENT OFFICE.

FRANK W. MERRICK, OF BOSTON, MASSACHUSETTS.

GUIDE OR GUARD DEVICE FOR WORK-PENETRATING TOOLS OF SEWING AND OTHER MACHINES.

1,408,821.

Specification of Letters Patent.

Patented Mar. 7, 1922.

Application filed June 28, 1918. Serial No. 242,470.

To all whom it may concern:

Be it known that I, FRANK W. MERRICK, a citizen of the United States, residing at Boston, in the county of Suffolk, State of Massachusetts, have invented a certain new and useful Improvement in Guide or Guard Devices for Work-Penetrating Tools of Sewing and other Machines, of which the following is a specification, reference being had 10 therein to the accompanying drawings.

The general object of the invention is to provide improved means for preventing deflection or bending of work-penetrating tools such, for instance, as the awl or needle of a 15 sewing machine, while entering or feeding the work.

The invention provides in connection with a reciprocating tool such as aforesaid an anti-deflection guide or guard which is actuated toward and from the surface of the 20 work, being thereby given intermittently a working position at or near the said surface in which it cooperates with the said tool for the purpose stated, and alternately there- 25 with being retracted so that it will not interfere with the thread or with other parts in the performance of their functions.

The invention is applicable in connection 30 with a reciprocating tool employed merely to pierce the work, but finds its maximum degree of usefulness in connection with a reciprocating tool which performs or assists in performing the operation of feeding the work along. In such connection the device 35 serves as a brace which prevents springing of the tool at the beginning and end of the respective feed-movements, or during the feed-movements, whereby variations from the standard feed-length are obviated. A 40 characteristic of the invention is a differential extent of movement of the guide or guard as compared with that of the tool. According to one part of the invention the guide or guard is actuated positively by means of 45 actuating connections having combined therewith a gauge or presser contacting with the work and controlling the limit of the throw of the device toward the work so that the 50 said limit is varied automatically to compensate for variations in the thickness of the work. The said gauge or presser may be the presser-foot of the machine. According to another part of the invention, the carrier for the guide or guard and the carrier for 55 the tool with which the device cooperates are mounted concentrically, so that the con-

centric mounting of the two carriers avoids the danger of tool-deflection by the guide or guard itself which would be likely if the two carriers were mounted side by side, especially as a result of wear. In effect, the tool and guide or guard are mounted so that both work upon the same longitudinal axis. If they were mounted to work on different axes, any wear of the parts, and resulting slack, would result in displacement of the tool to one side or the other, and also allow the tool to be deflected by the work. The invention includes special provisions for connecting the tool and guide or guard with 60 their respective carriers.

The invention is illustrated by the accompanying drawings, which show the preferred embodiment of the different features thereof and also a modified embodiment of some of 65 its features.

Fig. 1 is a side elevation of the preferred embodiment.

Fig. 2 is a front elevation thereof.

Fig. 3 is a partly sectional view of the reciprocating tool and guide or guard of Figs. 1 and 2, and their carriers.

Figs. 4 and 5 are views similar to Fig. 1 but showing the parts in different positions, with some portions broken away and others 70 in section.

Fig. 6 is a side elevation of a wax thread sewing machine having applied thereto the modified embodiment aforesaid.

Fig. 7 is a front elevation, and Fig. 8 a 75 view in vertical section, of the awl, the guide or guard, the carriers therefor, and the means of actuating the guide or guard and its carrier from the awl-carrier, of the said modified arrangement.

Fig. 9 is a view in horizontal section on line 9, 9, of Fig. 7.

Having reference first to Figs. 1 to 5,—

At 1 is the reciprocating tool in connection with which I employ the guide or guard aforesaid, and at 2 is the preferred form of the said guide or guard. In this case the tool 1 is an awl, for instance that of a wax-thread sewing machine, and the said awl and the guide or guard are secured to carriers 3 and 4 which are mounted in manner providing for vertical reciprocating movements of the carriers. The general construction shown pertains to the type of machine having an awl-feed or needle-feed and accordingly the two carriers are mounted in connection with a feed-arm or lever 5 in

manner to provide for the said vertical reciprocating movements relative to the said feed-arm or lever. To provide for the feed-movements of the latter, it is shown as hung 5 at its upper end, as heretofore usual, upon a pivot-screw 6, which in practice is engaged with a portion (not shown) of the fixed head of the machine. In practice, also, the feed-arm or lever has operatively combined 10 therewith automatic means (not shown) of well-known character by which swinging movements of predetermined extent are imparted thereto for the purpose of effecting the feeding of the work 7, resting upon 15 work-support 8, through the engagement of the tool with the work. Means of well-known character for reciprocating the tool vertically is shown, comprising the link 9 having its lower end connected pivotally 20 with the carrier 3, an arm 10 to which the upper end of the said link is connected pivotally, and a rockshaft 11 to which the said arm is attached, such rockshaft having combined therewith in practice, as usual, means 25 (not shown) for rocking the same.

The guide or guard 2 preferably cooperates with the tool at different sides of the latter, more especially in the direction of the line of feed. The illustrated form thereof 30 is tubular and surrounds and fits the tool 1, as shown best in Fig. 3. Such view also shows clearly the feature of making the carrier 4 for the guide or guard as a sleeve, and arranging it to enclose the carrier 3 for the 35 tool so as to secure in the case of the two carriers the concentric mounting to which reference has been made. The sleeve-like carrier 4 is fitted to a guide-bearing in the lower portion of feed-arm 5. The top portion of 40 tool-carrier 3, above the upper end of carrier 4, is fitted to a guide-bearing in the upper portion of the arm 5.

The means for reciprocating the guide or guard in proper coordination with the tool 1 45 may vary more or less in different embodiments of the features of the invention. In most cases the means for reciprocating the said tool vertically is adapted to be utilized for reciprocating the guide or guard also, 50 and in the present instance is shown as thus utilized, in conjunction with connections embodying certain special features of invention. Thus, the motion-transmitting link 9 is connected by means of a link 12 to links 55 13, 14, having their meeting ends connected together pivotally, as at 15, and having the upper end of the link 13 connected to an abutment-pivot 16 and the lower end of the link 14 connected pivotally at 17 with the 60 carrier 4 of the guide or guard. The link 12 is connected with the other links at the point 15.

The arrangement is such that when arm 10 and link 9 are in the elevated position 65 shown in Fig. 4, with tool 1 correspondingly

elevated, the links 13, 14, occupy the relatively bent or angular position shown in such figure, with the guide or guard 2 elevated also. As arm 10 and link 9 descend, causing tool 1 to move toward the work, 70 the thrust transmitted through link 12 carries the links 13, 14, downward, causing them to straighten out into line with each other and carrying the guide or guard 2 down so that it arrives in contact with the 75 upper surface of the work, or in the pre-determined close proximity thereto, before the point of the tool enters such surface. Fig. 1 illustrates this stage, with the links 13, 14, nearly in a straight line with each 80 other. In the further descent of arm 10 and link 9, which moves the tool down into the work, and in the first part of the lifting movement, the link 12 merely operates to swing the links 13, 14, laterally to and 85 slightly past dead center with relation to pivots 16, 17, and back to the position in Fig. 1, without occasioning any perceptible vertical movement of the guide or guard. This insures a prolonged dwell of the guide 90 or guard in its working position at the surface of the work while the feed-movement of arm 5 and tool 1 takes place. Continued upward movement of arm 10 and link 9, operating to withdraw tool 1 from the work, 95 also acts reversely through link 9 to return the links 13, 14, to their relative positions shown in Fig. 4, thereby raising the guide or guard into its withdrawn position.

Preferably, although not necessarily in all 100 cases, the limit of the throw of the guide or guard toward the work is controlled as hereinbefore indicated by means of a gauge or presser contacting with the work and operating to vary the said limit automatically 105 so as to compensate for variations in the thickness of the work. In the illustrated construction the presser-foot 18 is utilized as a gauge for the said purpose. The said presser-foot, as usual, is attached to the 110 presser-bar 19, which latter is acted upon by the spring 20 tending to keep the presser-foot down upon the top surface of the work and the latter pressed against the work-support 8. The said presser-bar is shown 115 mounted in guides in the stationary part 21 of the head of the machine, and also is shown as having combined therewith automatic presser-foot lifting mechanism A on the order of that of U. S. Letters Patent No. 120 891,210, dated June 16, 1908, for the purpose of lifting the presser-foot alternately with the formation of the stitches. As portions of different thickness of the work pass 125 between the presser-foot 18 and the work-support 8, the presser-foot and presser-bar change their position vertically, as illustrated by Figs. 1, 4 and 5. In Fig. 5 the work is somewhat thicker than in Figs. 1 and 4, and consequently the presser-foot and 130

presser-bar occupy a higher position in Fig. 5 than in Figs. 1 and 4. This vertical shift of the presser-foot and presser-bar under the control of the thickness of the work is made instrumental in controlling the limit of the throw of the positively-actuated guide or guard toward the work, by utilizing such shift to adjust the height of abutment-pivot 16 of the link 13. This is accomplished by engaging the said abutment-pivot with a bar 22 which is attached to the upper portion of the presser-bar and consequently rises and sinks in unison with the presser-bar and presser-foot. The said bar 22 occupies guideways in the upper portion of the part 21 of the machine-head. An increased thickness beneath the presser-foot will result in a higher position of the abutment-pivot 16, which will raise the limit of the throw of the guide or guard toward the work, and vice versa in the case of a decreased thickness.

The means shown in Figs. 1 to 5 for actuating the guide or guard is easy, smooth, and noiseless in operation and subject to very little wear.

The principles of the invention may be embodied variously in practice. The modification shown in Figs. 6 to 9 is of a type in which the guide or guard is actuated by frictional connections between its carrier and the carrier of the work-penetrating tool. Thus, as shown best in Figs. 7 and 8, the carrier 4 of the guide or guard 2 has attached thereto a collar 4^a from which extends upward a plate 4^b having a longitudinal slot 4^c formed therein. Within this slot is received a projecting portion of the collar 9^a with which the lower end of the motion-transmitting link 9, Fig. 6, is connected pivotally. This collar 9^a is fixedly mounted upon carrier 3. In this instance the link is actuated by means of a crank-pin 9^b on a rotating disk 9^c. A bent friction plate or spring 4^d is held against the outer face of the plate 4^b so that its curved end-portions make contact with the said face, by means of a screw 4^e, the threaded stem of which enters a threaded hole in the said collar 9^a while the flanged head of the screw engages with the bowed intermediate portion of the friction plate or spring. The plate 4^b thus is clamped frictionally between the exterior of collar 9^a and the extremities of the friction plate or spring. Thereby, the carrier 4 and guide or guard 2 are caused to move in unison with the carrier 3 and work-penetrating tool 1 until arrested by the contact of the guide or guard with the surface of the work in the movement toward the latter, or of the upper end of the plate 4^b with a suitable stop, as for instance the underside of the portion 5^a, Fig. 6, of the feed-arm 5, in the movement away from the work.

Fig. 8 shows the preferred mode of com-

bining the work-penetrating tool with its carrier 3. In this view the carrier 3 is bored longitudinally from end to end, the bore being slightly enlarged at the lower end of the carrier so as to form a chuck-receiving chamber, and its mouth being slightly flared. Within the said chamber is placed a split chuck 30 that is adapted to receive within its jaws the shank of the tool 1. The jaws of this chuck having flaring external enlargements to fit within the flared mouth of the enlarged bore of the carrier 3. The chuck is engaged with the lower end of a rod 31 occupying the greater portion of the length of the bore of the carrier 3, and in this instance projecting slightly above the top of the carrier. The engagement between the rod 31 and the chuck is effected in this instance by having the rod formed with a reduced lower end-portion which is screwed into a threaded hole in the upper end of the chuck. Upward movement of the rod and chuck within the bore of the carrier 3 will cause the flaring external portions of the chuck-jaws to bear against the inside of the flaring mouth at the lower end of the carrier, and thereby the chuck-jaws will be pressed into firm engagement with the shank of the tool 1. This movement of the rod is provided for in the present instance by forming a screw-thread upon its upper end-portion, and placing in engagement therewith a nut 32 which makes contact with the upper end of the carrier 3. By tightening up this nut the rod 31 is drawn upward so as to cause the chuck to close upon and hold the shank of the tool. By loosening the nut, the rod may be freed so as to permit it to move down in order thereby to relieve the grip of the chuck-jaws upon the tool-shank.

Guide or guard 2 is shown (see more particularly Fig. 3) detachably combined with the lower end of its carrier 4 by being formed with a tubular, internally screw-threaded, hub-portion screwing upon an externally screw-threaded portion of reduced diameter of said lower end.

What is claimed as the invention is,—

1. The combination with a reciprocating work-penetrating tool, a carrier-bar therefor, means for actuating said carrier-bar, an anti-deflection guide or guard for said tool, and a reciprocating carrier for said guide or guard, of a toggle connecting with said carrier and with a suitable abutment, and an intermediate link participating in the movement of the carrier-bar and connecting with said toggle, whereby differential movement of the carrier and the guide or guard relative to the tool is produced.

2. The combination with a reciprocating work-penetrating tool, a carrier-bar therefor, an anti-deflection guide or guard for said tool, and a reciprocating carrier-sleeve for said guide or guard mounted concentri-

cally with said carrier-bar, of a toggle connecting with said carrier-sleeve and with a suitable abutment, and an intermediate link participating in the movement of the carrier-bar and connecting with said toggle, whereby differential movement of the carrier-sleeve and the guide or guard relative to the tool is produced.

3. The combination with a work-gauge
10 or presser, a reciprocating work-penetrating
tool, a carrier-bar therefor, means for ac-
tuating said carrier-bar, an anti-deflection
guide or guard for said tool, a reciprocating
carrier for said guide or guard, and an abut-
15 ment adjustable in unison with the work-
gauge or presser, of a toggle connecting with
said carrier and with said abutment, and an
intermediate link participating in the move-
ment of the carrier-bar and connecting with
20 said toggle, whereby the latter and the car-
rier with its guide or guard are actuated.

4. The combination with a reciprocating
work-penetrating tool, of an anti-deflection
guide or guard therefor, a common actuator
25 for both thereof, links pivotally connecting
with each other, one thereof also connecting
with the guide or guard and the other with
an abutment, and a motion-transmitting link
intermediate said actuator and said links.

30 5. The combination with a work-contact-

ing gauge or presser, and a reciprocating
work-penetrating tool, of an anti-deflection
guide or guard for said tool, a common actuator
35 for the tool and the guide or guard, links
pivotally connecting with each other, 35
one thereof also connecting with the guide
or guard and the other with an abutment in
connection with the gauge or presser, and a
motion-transmitting link intermediate said
actuator and said links.

40 6. In combination, concentrically-mount-
ed tubular carrier-bars, an anti-deflection
guide or guard carried by the outer one, a
work-penetrating tool, a split chuck receiv-
ing said tool and occupying a chamber in the 45
inner carrier-bar, and an operating-rod for
said chuck extending lengthwise through
the latter carrier-bar.

7. In combination, concentrically-mount-
ed carrier-bars, a work-penetrating tool car-
ried by the inner one, and an anti-deflection
guide or guard detachably screwing upon
50 the lower end of the outer carrier-bar and
arranged to cooperate with the said tool.

In testimony whereof I affix my signature 55
in presence of two witnesses.
